UNITED STATES PATENT OFFICE.

MICHAEL GILMORE AND NELLIE L. GILMORE, OF PHOENIXVILLE, PENNSYLVANIA.

BATH-TUB ATTACHMENT.

No. 919,848.

Specification of Letters Patent.

Patented April 27, 1909.

Application filed February 2, 1909. Serial No. 475,567.

To all whom it may concern:

Be it known that we, MICHAEL GILMORE and NELLIE L. GILMORE, citizens of the United States, and residents of Phoenixville, 5 in the county of Chester and State of Pennsylvania, have made certain new and useful Improvements in Bath-Tub Attachments, of which the following is a specification.

This invention is an improvement in frames for application to bath tubs, and has for an object to provide a frame which can be applied to and removed from the tub, and will afford facilities for holding a wash bowl and a soap dish, and the invention consists in certain novel constructions and combinations of parts as will be hereinafter described and claimed.

In the drawing, Figure 1 is a top plan view, and Fig. 2 is a side view, partly in section, 20 of a frame embodying our invention applied to a bath tub, and Fig. 3 is a cross section on about line 3—3 of Fig. 2.

The frame A has the open ring B adapted to receive a wash bowl, see dotted lines, Fig. 25 2, and the rod forming the bowl or basin ring B is twisted for a short distance at B² and terminates in a stem C, which is adjustably held by a screw D² in a socket D' of a foot D to rest against the rim of the tub. Suitable pads B' may be provided, as shown in 30 Figs. 1 and 2 of the drawing.

At a point diametrically opposite the twisted length B², the rods forming the ring B are twisted for a short length at B³ then 35 opened to form a dish holding frame E for a soap dish, then twisted for a short length at B⁴ and connected with the shank F' of the foot F. The feet D and F are padded preferably by rubber plates d and f on the under- 40 side of the feet as shown in Fig. 2. These pads prevent injury to the tub and also operate to prevent the frame from slipping

when applied to the tub as shown in Figs. 1 and 2.

In use the frame is supported between and 45 from the opposite rims of the tub, and is thus firmly held when in use. The connection between the stem C and the socket D' permits the accurate adjustment of the frame to fit tubs of different sizes. 50

The invention will be found useful for general use, but especially so in boarding houses among the laboring classes, as several of the frames can be arranged side by side in the same tub to enable several persons to wash 55 at the same time and each person can have his individual wash basin and soap dish.

We claim—

1. A frame for application to bath tubs having an open ring adapted to receive a 60 wash bowl and having its rods twisted to form a short length terminating in a stem, the rods at a diametrically opposite point from the said twisted length being twisted for a short length and then opened forming 65 a frame adapted to receive a soap dish, a foot beyond the soap dish frame, a foot having a socket receiving the terminal stem of the frame, and means for securing the stem adjustably in said socket substantially as 70 set forth.

2. A frame substantially as described having at its ends feet to rest upon the opposite rims of a tub and composed between its ends of rods twisted together and opened 75 at intervals forming a bowl holding ring, and a frame adapted to receive a dish substantially as set forth.

MICHAEL GILMORE,
NELLIE L. GILMORE.
